SCREEN TYPE TRANSFER AGENT DUPLICATING FORM

John R. Kendig, East Orange, N. J., assignor to
Gobin Smith, East Orange, N. J.

Application September 23, 1943, Serial No. 503,543

6 Claims. (Cl. 101—131)

This invention relates to a duplicator or reproducing sheet and it is one object of the invention to provide a sheet consisting of companion sections so arranged and of such nature that when properly folded the sheet may have writing or the like typed or otherwise inscribed thereon and the inscribed sheet then passed through a duplicating machine and copies of the inscribed sheet reproduced.

Another object of the invention is to provide a duplicator sheet including a master sheet, a carbon sheet, and an anti-smudge sheet which serves to prevent the carbon sheet or section from smearing the master sheet or matter inscribed thereon, the sections or sheets being so arranged that by properly folding them, the carbon sheet may be disposed back of the master sheet with the anti-smudge sheet therebetween to protect the master sheet before use and while being carried to a duplicating machine, the carbon sheet being disposed between the anti-smudge sheet and the rear face of the master sheet with its coated surface confronting the master sheet while inscribing matter upon the front face of the master sheet, and the master sheet being turned to dispose it rearwardly of the carbon sheet and the anti-smudge sheet with its rear face presented outwardly during passage of the duplicator through a duplicating machine.

Another object of the invention is to so form and arrange the sheets or sections that while inscribing matter upon the master sheet a portion of the anti-smudge sheet may be disposed between the carbon sheet and the rear face of the master sheet and thus act as a shield to prevent predetermined portions of matter inscribed upon the front face of the master sheet from being reproduced upon the rear face of the master sheet.

Another object of the invention is to provide a sheet of the character described which includes a plurality of sections permanently engaged with each other so that they will always be ready for use, a marginal portion of the carbon sheet being left uncoated so that soiling of a person's hands by contact with the coated surface of the carbon sheet will be prevented.

Another object of the invention is to provide a device of this character which is simple in construction, efficient in operation, and cheap to manufacture.

The invention is illustrated in the accompanying drawing wherein:

Figure 1 is a perspective view of the improved reproducing sheet.

Figure 2 is a view looking at the front of the reproducing sheet as it appears when initially folded.

Figure 3 is a sectional view taken transversely through Figure 2 upon the line 3—3.

Figure 4 is a view showing the sheet as it appears when folded for inscribing matter thereon.

Figure 5 is a sectional view taken along line 5—5 of Figure 4.

Figure 6 is a sectional view taken along line 6—6 of Figure 4.

Figure 7 is a view showing the sheet folded for passage through a duplicating machine.

Figure 8 is a sectional view taken along line 8—8 of Figure 7.

Figure 9 is a view similar to Figure 7 looking at the exposed rear face of the master sheet.

Figure 10 illustrates a slightly modified construction.

This improved reproducing sheet consists briefly of a master sheet 1, a carbon sheet 2 and an anti-smudge sheet 3. These sheets or sections 1, 2 and 3 may be formed from a single sheet of paper which is creased to set off the sheets or sections from each other and permit them to be easily turned from one position of adjustment to another or they may consist of separate sheets united along adjoining side edges to permit turning and folding of the sheets.

The sheet 3 is chemically treated so that carbon will not adhere to it. The front face of sheet 1 has a form 4 printed thereon in permanent ink and upon its rear face is a corresponding reversely printed form 5 shown in Fig. 9, the form 5 being printed in carbon from the carbon sheet 2 as the form is printed upon the front face of the sheet so that when the reproducing sheet is passed through a duplicating machine the form will be reproduced as well as matter imprinted with carbon upon the rear face of the master sheet. The carbon sheet 2 has one face coated with carbon which terminates in spaced relation to the free side edge thereof so that this uncoated portion 2' of the carbon sheet may be grasped without carbon getting upon the fingers of the person handling the same. In many instances it is desired to permit matter to be inscribed upon the front face of the master sheet without certain portions of the same being produced in carbon upon the rear face of the master sheet. Therefore, a portion of the anti-smudge sheet has been set off from the remainder of the sheet by lines of scoring so that this portion 3 of the anti-smudge sheet may be severed along the lines of scoring and disposed in covering and

shielding relation to the coated surface of the carbon sheet while the remaining portion of the anti-smudge sheet is disposed back of the carbon sheet and the exposed portion of the coated face of the carbon sheet engaged the rear face of the master sheet. While there has been shown one portion 3' it is to be understood that additional portions of this nature may be provided by properly scoring the anti-smudge sheet.

The duplicator as manufactured and supplied to the user is folded as shown in Figures 2 and 3 to dispose the master sheet at the front and the anti-smudge sheet between the master sheet and the coated surface of the carbon sheet. Since the coated surface of the carbon sheet is disposed inwardly, the carbon will not be rubbed off or soil other sheets of a stack of duplicators. When the duplicator is used the operator grasps the carbon sheet by the uncoated edge portion 2' thereof and turns it to the position shown in Figures 4 and 5. In this position the carbon sheet is disposed between the anti-smudge sheet and the master sheet with its coated surface confronting the master sheet and bearing against the rear face thereof. While the uncoated side edge portion 2' of carbon sheet 2 has been shown folded, it is to be understood that the carbon sheet may be of such width that its uncoated edge portion may be left flat as shown in Figure 10. With the duplicator so folded it may be placed in a typewriter, or other suitable machine and data typed thereon, or subject matter may be inscribed upon the front face of the master sheet with a pen or pencil. As subject matter is typed or otherwise inscribed upon the front face of the master sheet a reproduction of the same in reverse will be produced upon the rear face of the master sheet by action of the carbon sheet and since the reproductions on the rear face of the master sheet are directly back of the originals on its front face they will occupy the same positions in the form marked in reverse upon the rear face that they do in the form upon the front face.

After the subject matter has been inscribed upon the front face of the master sheet, it is removed from the typewriter and refolded in its original condition so that the anti-smudge sheet will be disposed between the carbon sheet and the rear face of the master sheet and prevent smudging of the rear face of the master sheet. Figure 10 shows adjoining corner portions of the master sheet and an anti-smudge sheet cut to form a recess 5 through which the lower end of portion 2' is exposed. This permits the carbon sheet to be readily grasped by its lower free corner and the sheets easily turned from one position of assembly to another. In case it is desired to prevent certain portions of the subject matter typed upon the master sheet from being reproduced upon the rear face thereof, the anti-smudge sheet is severed along scored lines and a portion 3' of the anti-smudge sheet disposed in front of the carbon sheet, as shown in Figure 6, and since the anti-smudge sheet is chemically treated to prevent carbon from adhering to it, no reproductions of subject matter upon the portion of the master sheet in front of the portion 3' of the anti-smudge sheet will appear upon the rear face of this portion of the anti-smudge of the anti-smudge sheet. It will thus be seen that both faces of the anti-smudge sheet will at all times be free from carbon and cannot cause the master sheet or other sheets to be smudged or otherwise disfigured by carbon adhering to it.

In order to make a reproduction of the subject

matter upon the master sheet, its rear face bearing subject matter in reversal, and in copying ink or carbon must be pressed against a sheet of paper onto which the copy is to be produced. In order to do so, the duplicator and a sheet of paper are passed through a duplicating machine but before doing so the duplicator must be folded as shown in Figures 7, 8 and 9. Referring to these figures, it will be seen that the master sheet is turned to dispose it back of the carbon sheet, as shown in Figures 7 and 8, instead of in front of the anti-smudge sheet with its rear face presented rearwardly and since this face of the master sheet bears the reproduction of the subject matter in carbon and a sheet of paper to receive the copy is disposed against this face of the master sheet, pressure of the duplicating machine as the duplicator and the sheet of paper are passed through it will cause an impression of the subject matter to be transferred to the sheet of paper. An exact copy of the subject matter typed or otherwise inscribed upon the master sheet will thus be reproduced upon the sheet of paper. Numerous copies may thus be produced by repeatedly passing the duplicator and a sheet of paper through a duplicating machine. After a sufficient number of copies have been made, the master sheet is refolded to its initial position and the duplicator may be put away for future use.

From the foregoing description, the construction and operation of my duplicating form will be readily understood and it will be seen that I have provided a comparatively simple, inexpensive and efficient means for carrying out the various objects of the invention.

While I have particularly described the elements best adapted to perform the functions set forth, it is apparent that various changes in form, proportion and in the minor details of construction may be resorted to, without departing from the spirit or sacrificing any of the principles of the invention.

Having thus described the invention, what I claim is:

1. A duplicator comprising a single sheet of paper having side edges at its ends and upper and lower edges, said strip being foldable in spaced relation to its ends to provide end sections and an intermediate section integral with the end sections, one end section constituting a master sheet having front and rear faces and the other end section having a face coated with a transfer agent and constituting an anti-smudge sheet, said intermediate sheet constituting an anti-smudge sheet disposed between inner side edges of the master sheet and the carbon sheet, said duplicator being initially folded along opposite side edges of said anti-smudge sheet to dispose the anti-smudge sheet between the rear face of the master sheet and the coated face of the carbon sheet, said duplicator being foldable along the said side edges of the anti-smudge sheet to dispose the carbon sheet between the anti-smudge sheet and the rear face of the master sheet with its coated face confronting the rear face of the master sheet for reproducing upon the said rear face of the master sheet markings inscribed upon the front face of the master sheet, and the duplicator being also foldable to dispose the master sheet back of the carbon sheet with its rear face exposed for reproducing matter thereon when the duplicator is passed through a duplicating machine together with a sheet of paper to receive an impression from the rear face of the master sheet.

2. A duplicator comprising a single strip hav-

ing end sections constituting a master sheet and a carbon sheet, and an intermediate section constituting an anti-smudge sheet disposed between and integrally connected with the master sheet and the carbon sheet, said duplicator being creased and foldable along side edges of the anti-smudge sheet to selectively dispose said sheets in predetermined face to face relation to each other.

3. A duplicator comprising a master sheet, a carbon sheet, and an anti-smudge sheet between the master sheet and the carbon sheet having opposite side edges united with inner side edges of the master sheet and the carbon sheet, said duplicator being foldable along side edges of the anti-smudge sheet to selectively dispose said sheets one upon another in predetermined relation to each other, and said anti-smudge sheet having scored lines defining a portion adapted to be severed along the scored lines and freed from the remainder of the anti-smudge sheet whereby the said freed portion may be disposed in covering relation to a corresponding portion of the coated face of the carbon sheet to shield a portion of the rear face of the master sheet when the remainder of the carbon sheet is disposed back of the master sheet with its coated surface confronting the master sheet.

4. A duplicator comprising a master sheet having front and rear faces, a carbon sheet having one face coated with carbon, and an anti-smudge sheet disposed between and connected with inner side edges of the master sheet and the carbon sheet, the said sheets being foldable along side edges of the anti-smudge sheet to move the carbon sheet from a position back of the anti-smudge sheet with its coated face confronting

the same to a position between the anti-smudge sheet and the rear face of the master sheet with its coated face confronting the rear face of the master sheet, said master sheet having a form 5 printed upon its front face and reproduced upon its rear face by action of the carbon sheet, and said duplicator being also foldable to dispose the anti-smudge sheet over the coated surface of the carbon sheet and the master sheet back of the carbon sheet with its marked rear face exposed for reproduction of matter thereon when the duplicator is passed through a duplicating machine.

5. A duplicator comprising a master sheet, a carbon sheet, and an anti-smudge sheet disposed between the master and carbon sheets and having side edges connected with adjoining side edges of the master sheet and the carbon sheet, said duplicator being foldable along side edges of the 10 anti-smudge sheet to dispose the sheets in predetermined face to face relation to each other.

6. A duplicator comprising a master sheet, a carbon sheet, and an anti-smudge sheet disposed between and connected with side edges of the master and carbon sheets, said duplicator being 15 foldable along opposite side edges of the anti-smudge sheet to dispose the sheets in predetermined relation to each other, and the said master sheet and anti-smudge sheet having adjoining 20 corner portions cut therefrom to register and form the folded duplicator with a recess exposing a corner portion of the carbon sheet whereby the carbon sheet may be grasped and held while turning the sheets from one position of assembly to another.
